COMBINATION CHAIR AND TABLE

Leo Dion, Detroit, Mich.

Application March 2, 1946, Serial No. 651,549

3 Claims. (Cl. 155—43)

1

The invention herein described and illustrated in the accompanying drawings relates to furniture and particularly household and porch furniture and has for one of its objects to provide a combination table and chair.

This invention has for another object to provide a convertible table and chair.

A further object of this invention is to provide a piece of furniture capable of use either as a card table or a side chair.

There is also the object of providing a table and chair combination which is formed of a maximum of four pieces of material, or which may be formed of only three pieces of material, or which could be formed of a single sheet of plastic metal or plywood if found desirable.

Other features and advantages will become more readily apparent from the following description and the accompanying illustrative drawings in which:

Figure 1 is an end elevational view of the invention,

Figure 2 is a front elevational view of the invention,

Figure 3 is a view similar to Figure 1 showing the article in a different position,

Figure 4 is a perspective view of the device shown as a chair,

Figure 5 is a similar view shown as a table,

Figure 6 is a detail perspective view of the parts from which the device is made, and

Figure 7 is an end view of a modification.

In the accompanying drawings, 10 refers to the complete device which consists of a chair 11 and table 12, both being one and the same piece of furniture shown in two inverted positions relative to one another. The article as illustrated in Figures 1 to 5 consists of four members 14, 15, 16 and 17 respectively.

In the position shown in Figure 1 of the drawings 14 is the rear support for the chair 11, while 15 is a combination seat 18 and back rest 19, and members 16 and 17 are the arms of the chair. To the upper inner edge 20 of the member 14 the returned flange 21 of the upper edge 22 of the back 19 is fixedly attached. From the edge 22 the back 19 inclines down and outwardly and below the arms 16 and 17 is curved out as at 23 to form the substantially horizontal seat 18. The front legs 24 and 25 of the chair are secured to the down curved forward edge 26 of seat 18 as at 26' and 27' from which point they continue up vertically to form arm supports 28 and 29 and from their upper bends 30 and 31 they incline down and extend inwardly to the slots 32 and 33

2

in the opposite side edges 34 and 35 of the member 19, to form the arms 36 and 37 of the chair. The inner ends 38 and 39 of said arms seat in and project through the slots 32 and 33 and the extreme terminants are inclined down to form flanges 40 which are fixed to the substantially central portion 42 and 43 of said member 14 to provide rigid bracing therefor.

When the article is to be used as a bridge table it is turned over upon the front legs 24 which form a support base from which the members 18', 19', 36' extend to form legs for the table member 14' which forms the table 12, the arms 36' also forming other legs for the table 14'.

From the foregoing it will be seen that two complete pieces of furniture are provided from only the four members 14 to 17 seen in Figure 6 of the drawings. While these members are preferably cut from sheet plastic, it is evident that they may be made from metal or plyboard.

In Figure 7 of the drawings is shown a modification in which it will be seen that the entire device 44 may be cut from a single sheet of material, the members 45, 46, 47, 48, 49 and 50 being integral throughout and shaped to form the article 46 usable either as a chair or table.

Changes in shape, size and rearrangement of details and parts such as come within the purview of the invention claimed may be resorted to, in actual practice, if desired.

Having thus described the invention that those versed in its particular art will fully understand how to make and use the same, as well as its functions, and without having attempted to detail all of the forms in which it may be made, all of its advantages, or all of the uses to which it may be put, it is declared that which is claimed as new and sought to be protected by Letters Patent is:

40. 1. A combination chair and table comprising a substantially flat rear support adapted to be used selectively as a table top and chair support, angular support members secured to said rear support adjacent the longitudinal center thereof, 45 said support members being adapted to serve selectively as arm rests and a complete leg frame and base, means secured to said rear support interlocked and secured to said angular support members for strengthening said support members 50 and for seating purposes, said means comprising a flat sheet having bends therein to form the seat and having slots interconnected with said support members.

2. In a combination chair and table, a substantially flat rear support, means secured adja-

cent the longitudinal center of said rear support for selectively supporting said rear support and for serving as arm rests, a flat sheet member having bends therein secured to said rear support, said selective means comprising flat support members having relatively angularly disposed sections, a first of said sections of each flat support being secured to said rear support and forming arm rests.

3. In a combination chair and table, a substantially flat rear support, means secured adjacent the longitudinal center of said rear support for selectively supporting said rear support and for serving as arm rests, a flat sheet member having bends therein secured to said rear support and said selective means forming a leg frame and for seating purposes, said selective means comprising flat support members having relatively angularly disposed sections, a first of said sec-

tions of each flat support being secured to said rear support, a second of said sections of each flat support forming a leg base, and said sheet member having slots operatively engaging the first section.
